(57) CLAIM

The ornamental design for a grater for food products, as shown and described.

DESCRIPTION

FIG. 1 is a partial perspective view of a grater showing the new design. The Chrysler building is shown in dotted lines for illustrative purposes only to indicate the overall shape of a grater and forms no part of the claimed design.

FIG. 2 is an enlarged perspective view of FIG. 1 showing front and right side views thereof; the rear and left side being a mirror image thereof;

FIG. 3 is a top plan view thereof; and,

FIG. 4 is a bottom elevation view thereof.
